UNITED STATES PATENT OFFICE.

FRANK S. RODE, OF JEANNETTE, PENNSYLVANIA.

GAME APPARATUS.

Application filed December 17, 1925. Serial No. 76,073.

This invention relates to new and useful improvements in game apparatus.

The primary object of the invention is to provide apparatus by means of which many different games involving the production of competitive counts or scores may be played.

A further object of the invention is to provide a game apparatus embodying novel features of construction which will permit the same to be manufactured in large quantities and at a small cost, whereby the apparatus may be properly termed a practical article of manufacture.

Other objects and advantages of the invention will be apparent during the course of the following description.

In the accompanying drawings forming a part of this specification and in which like numerals are employed to designate like parts throughout the same,

Figure 1 is a perspective view of the game apparatus constructed in accordance with this invention,

Figure 2 is an enlarged fragmentary front elevational view of the upper portion of the apparatus and shows the manner in which the same is used,

Figure 3 is a transverse sectional view taken upon line III—III of Fig. 2,

Figure 4 is a transverse sectional view taken upon line IV—IV of Figure 2,

Figure 5 is a vertical sectional view taken upon line V—V of Fig. 2,

Figure 6 is a fragmentary vertical sectional view of a part of the lower portion of the apparatus,

Figure 7 is a fragmentary front elevational view of a slightly modified form of apparatus, and

Figure 8 is an edge plan view of the form shown in Figure 7.

In the drawings, wherein for the purpose of illustration is shown a preferred embodiment of this invention, the numeral 5 designates what will be termed the board part of the apparatus and which is formed from a sheet of metal bent to provide the end walls 6 which are rolled at their outer edges to form the finishing beads 7. The upper edge of the board 5 is bent forwardly to form a top wall 8 and then downwardly to form the depending flange 9. The upper portion of one of the end walls 6 has its edge bent laterally to form a flange 10 which cooperates with the flange 9 for holding in place a relatively small front wall 11 that

extends the full width of the board 5 and depends for a relatively small portion of its length. The lower edge of the front wall 11 is rolled upwardly and inwardly to form the finishing bead 12.

This board 5 is supported by means of the stands which are designated in their entirety by the reference character 13. Each one of these stands is formed from a single strand of wire which has its ends 14 inserted through apertures 15 formed in an end wall 6, as best illustrated in Fig. 1. The intermediate portion of each strand is bent to provide the downwardly diverging parts 16, the horizontal part 17, and the looped portions 17^a. It will be seen that the parts 16 and 17 form a triangle while the loops 17^a depend below the horizontal part 17 and constitute feet portions intended to engage a supporting surface, as best illustrated in Fig. 1.

Extending between the horizontal portions 17 is a sheet metal platform 18 which has its ends 19 rolled around the portions 17 and is further provided with depending side flanges 20. The top portion of this platform 18 is formed with the plurality of depressions 21. It will be seen that the standards 13 support the board 5 in a vertical plane and that the platform 18 with its depressions or pockets 21 is located below the bottom edge 5^a of the board 5, the plane in which the board 5 is located intersecting the depressions or pockets 21.

In Figs. 1, 2, 4, 5 and 6 the board 5 is illustrated as having struck therefrom a multiplicity of disks 22 which are left connected to the board 5 by the stems 23. In striking these disks 22 from the board 5, the same are moved forwardly of the plane occupied by the board and are all arranged in a common plane extending in parallelism with the board. Figs. 4 and 5 clearly illustrate the fact that these struck out disks 22 cooperate with the board 5 for forming tortuous paths extending from the top to the bottom of the board and through which a coin or disk may travel without being permitted to fall or move away from the front face of the board.

In Figs. 1 to 3 inclusive, the upper portion of the board 5 and the front wall 11 are illustrated as being formed with horizontally aligned lateral projections 24 and 25 which have their ends overlapped at 26 for connecting the same together. The upper edges 27 of these two extensions 24 and

25 are rolled over to form finishing beads which also leave these edges disconnected and provide a space or slit between the same. The lower edge of the front extension 25 is bent laterally toward the rear extension 24, as at 28 while a narrow strip 29 is bent forwardly from the rear extension 24. These two portions 28 and 29 aid in retaining the extensions 24 and 25 properly spaced in respect to each other and constitute a short runway 30, the function of which will be described at a later point. From the edges of the members 28 and 29 to the inner faces of the turned over, overlapping ends 26 is provided a slot 31.

A length of spring wire 32 is provided and has its lower end threaded through apertures 33 formed in one end wall 6 while its upper end portion 34 is threaded through the slot 31 and between the extensions 24 and 25 to project upwardly beyond the upper beaded edges 27 of the same. This strand of spring wire is flattened at 35, which is the portion located between the extensions 24 and 25.

This spring wire 32 is intended to function as a catapult for projecting the disk or projectile 36, see Fig. 2.

In Figs. 7 and 8 there is shown a slightly modified form of board 5. This board, instead of having the disks 22 stamped therefrom, is provided with the disks 22^a which are supported in spaced relation to the front face of the board 5 by means of the centrally located stems 23^a. These disks 22^a also cooperate with the board 5 for forming a multiplicity of tortuous paths through which a coin or disk may travel from the upper portion to the lower portion of the board.

The operation of this device may be described in detail as follows:

Attention is first invited to Fig. 2 where in a disk, coin, or projectile 36 is illustrated as having been dropped through the space provided between the upper edges 27 of the extensions 24 and 25. The element 36 is illustrated in full lines in this figure as resting upon the runway 30. By drawing the upper end 34 of the strand of spring wire 32 or catapult rearwardly into the position shown in dotted lines, the strand of wire will be placed under tension and the element 36 will drop into its dotted line position. By releasing the end 34 of the spring wire with a snap, the said wire will flex into its full line position and will project the element 36 into the chamber formed between the front wall 11 and the parallel portion of the board 5. It will be seen, by inspecting Fig. 5, that this chamber or chute is minus a bottom wall, whereby the element 36 will not be retained in the same and will be permitted to fall toward the disks 22. Figure 2 shows in dotted lines

the course of an element 36 after it has been projected or shot into the chamber by the spring wire or catapult 32. This coin will travel downwardly through any one of the many tortuous paths until it reaches the platform 18 located below the board 5 and comes to rest in one of the depressions or pockets 21. It will readily be seen that the coin will be prevented from falling away from or leaving the surface of the board 5 by the disks 22. This fact will be clearly noted by a close inspection of the element 36 in its various dotted line positions as illustrated in Fig. 2. In each of these positions, the edge of the element is never entirely free from between the disks 22 and the board 5.

It is not believed necessary to go to any great length in explaining the different types of games which may be played with this apparatus. It will be sufficient to merely state that the pockets or depressions 21 may be given numbers which vary in amount or value and competition may be established by endeavoring to project the coin or disk 36 so that it will travel through a suitable tortuous path to cause the same to come to rest in the pocket or depression bearing the number of greatest value. A further game that may be played is to allot the pockets or depressions 21 to different players and permit the latter to endeavor to deposit the greatest number of disks or players 36 in his particular pocket 21.

It is to be understood that the forms of this invention herewith shown and described are to be taken as preferred examples of the same, and that various changes in the shape, size, and arrangement of parts may be resorted to without departing from the spirit of the invention or the scope of the subjoined claims.

Having thus described the invention, I claim:

1. In apparatus of the type described, a vertical board, a multiplicity of disks scattered over the front face of said board and supported in a common plane parallel to the board, a player projecting means at the upper end of the board, and a platform having pockets located below the board.

2. In apparatus of the type described, a vertical board, an open bottomed chamber extending across the upper end of the board, a multiplicity of disks scattered over the front face of the board and supported in a plane parallel to the board, a player projecting means at one end of the open bottom chamber, and a platform having pockets located below the board.

3. In apparatus of the type described, a vertical board, an open bottomed chamber extending across the upper end of the board, a multiplicity of disks scattered over the front face of the board and supported in a

plane parallel to the board, a player projecting means at one end of the open bottomed chamber, a pair of standards for supporting the board, and a platform having pockets supported by the standards below the board.

4. In apparatus of the type described, a vertical board formed of sheet metal, a multiplicity of disks struck from said board and connected thereto to reside in a common plane parallel to the board, a player projecting means at the upper end of the board, and a platform having pockets located below the board.

5. In apparatus of the type described, a vertical board formed of sheet metal, a multiplicity of disks struck from said board and supported in a common plane parallel to the latter, an open bottomed chamber extending across the upper end of the board,

a player projecting means at one end of the chamber, a pair of standards for supporting the board, and a platform having pockets supported by the standards below the board.

6. In apparatus of the type described, a vertical board formed of sheet metal and having outwardly turned side edges to form side walls, a multiplicity of disks struck from said board and supported in a common plane parallel to the board, a top wall formed on said board, a front wall located at the upper end of the board and connected to the top and side walls, said top and front walls forming an open bottomed chamber, player projecting means at one end of the chamber, and a platform having pockets located below the board.

In testimony whereof I affix my signature.

FRANK S. RODE.
